METHOD AND APPARATUS FOR PREFOCUS-
ING LAMPSDuryea E. Elmendorf, Shaker Heights, Ohio, as-
signor to General Electric Company, a corpora-
tion of New York

Application June 21, 1937, Serial No. 149,455

12 Claims. (Cl. 176-3)

My invention relates to the manufacture of incandescent lamps and more particularly to a method and apparatus for automatically adjusting the bulb of a lamp with reference to the base or a portion thereof to accurately locate the filament in a predetermined position with respect to said base or portion thereof. Heretofore, such adjustment has been made manually with the assistance of optical means for showing the position of the filament and of mechanical means with which the position of the bulb was shifted.

One of the objects of my invention is to eliminate all manual operations in the prefocussing of the lamp to reduce the cost and increase the speed and accuracy thereof.

According to my invention, the lamp bulb, in which the filament is sealed, is first mounted in approximately the correct relation to the base portion and near the focus of a reflector or other light beam projecting means. The said bulb is then moved about in the reflector to gradually increase the amount of light directed thereby onto a light-sensitive cell located some distance therefrom, until finally the reflected or redirected light concentrates on the light-sensitive cell and the filament is in the correct position. The specific procedure is to move the bulb axially in or out of the parabolic reflector in whichever direction causes an increase in the amount of light falling on the photocell and to stop this movement when the light peak is reached and the light falling on the cell begins to decrease. Following this movement, the bulb is moved in a lateral direction in the reflector until motion is again stopped, whereupon it is moved perpendicularly to the said lateral direction until stopped. This series of movements may not necessarily adjust the filament to the correct location and it is preferred that the same sequence of operations be performed a second or even a third time before the base or portion thereof is attached to the rest of the lamp and the operations are completed. A lens or other optical means may be provided to assist in directing the light from the reflector onto the photocell.

Other features and advantages of my invention will be apparent from the detailed description which follows and from the accompanying drawing of one species thereof.

In the drawing, Fig. 1 is a somewhat diagrammatic perspective view, partially in section, of apparatus comprising my invention, and Fig. 2 shows the electrical circuit therefor.

In the particular case illustrated in the drawing, the lamp 10, comprising the bulb 11, the

filament 12 which is sealed therein and the base 13 which is already cemented to the bulb 11, is adjusted automatically to a predetermined position with respect to the collar 14 which is subsequently united to the said base.

The collar 14 is of the type shown in French Patent 2,033,699, issued March 10, 1936, and is inserted in the holder 15. At the time of insertion, the fingers 16 are pulled back and collar 14 is placed in a recess in the holder 15 and registers 10 with pins (not shown) which enter into the locating holes 17 in said collar. The fingers 16 are held out of position by manual operation of a foot pedal (not shown) which moves rod 18 toward the collar 14, causing the slide plug 19 to 15 engage the end of fingers 16 and move them away from the recess in holder 15. The release of the foot pedal allows the fingers 16 to be moved inward into contact with the collar 14 by the spring 20 which surrounds the holder 15 and fingers 16 20 and pulls inward on said fingers. The lamp 10 is now placed in the apparatus, the base 13 thereof being passed through the aperture in the reflector 21 and inserted in the collar 14 and in the central aperture in holder 15, the bulb 11 being brought 25 against the suction cup 22. The opening in the collar 14 and the aperture in holder 15 are slightly larger than the base 13 in order to permit the adjustment of the lamp 10 necessary to bring the filament 12 to the correct location, the base 13 30 and the bulb 11 being supported by the suction cup 22. Before the adjustment takes place, the filament 12, which is connected through leading-in wires to the shell and end contact of the base 13, is connected to a source of electricity (not 35 shown) by the fingers 24 and 25 respectively. The fingers 24 and 25 are pivoted in an insulating portion of the holder 15 and are pressed against their respective base portions by the springs 26 and 27. In this instance, it is preferred that direct current 40 be applied to the filament 12 so that it is caused to emit a uniform amount of light.

As so far described, the filament 12 is located only approximately in the desired position. The correct position is determined by means connected 45 to the lamp 10 through the suction cup 22 which causes the lamp 10 to be moved in different directions in a regular order under the control of the photocell 28. In this case, the filament 12 is properly located with respect to the base collar 14 50 when the said filament 12 is located at a point behind the focus of the parabolic reflector 21 which causes substantially all of the light redirected thereby to fall on the lens 29. The lens 29 in turn redirects the light through the aper- 55

ture in the screen 30 onto the photocell 28. In some cases, and particularly when the smaller miniature incandescent lamps are being adjusted, it is more desirable that the filament 12 be properly located when it is at the focus of the reflector 21 and that the lens or lenses 29 be as large as the said reflector 21 so as to receive all the light therefrom. The screen 30 may be dispensed with if desired, since it is used only to shield the photocell 28 from stray light and, in this case, to limit the exposure of the photocell 28 to an equal amount in all directions as said photocell 28 is much longer than wide.

The lamp 10 is adjusted back and forth in three directions during the operation of the apparatus, one adjustment being crosswise vertically in the reflector and being produced when the electric motor 31 is operated and the slide 32, to which the suction cup 22 is attached by the arm 33, is moved in the ways of block 34. Another adjustment is crosswise of said reflector and at 90° to the other movement (i. e., horizontally) when electric motor 35 is operated and the block 34 is slid in the ways of block 36. In a third adjustment, the lamp is moved axially in and out of the reflector when the electric motor 37 is operated and block 36 is slid in the ways of the block 38. In each case, the electric motors 31, 35, 37 operate a screw 39 through a speed reducer 40 mounted directly thereon as a unit, and are fixedly mounted so that the screw 39 causes the slide 32 and blocks 34 and 36 to be moved. Each of the motors 31, 35, 37 is series wound with separate field windings for each direction of rotation.

The apparatus is placed in operation by momentarily closing the push button 41 (Fig. 2) which connects the coil 42 of the relay 43 to line conductor 44 through wires 45 and 45' and causes said relay 43 to operate. The coil 42 is also connected through wire 46 to the other line conductor 47. Once the circuit to the coil 42 is completed, it is energized and the armature 48 is shifted so that it engages a contact connected through lead 49, the armature 50 of a second relay 51 and leads 52 and 45 to the coil 42. This circuit causes the relay 43 to remain "closed".

The principal function of the relay 43 is to connect the leads from the separate field windings of motor 37 which are connected to the armatures 53 and 54 to the wires 55 and 56 which are attached to contacts engaged thereby leading to the reversing relay 57. At the particular instant illustrated, both coils 58 and 59 of the relay 57 are not energized and the armature 60 which is connected to the line conductor 44 is in engagement with a contact connected to wire 58 which causes one of the field windings of the motor 37 to be energized. The armature of the motor 37 is connected to the line conductor 47 and the energized field winding causes it to turn in a direction which can be assumed to be moving the lamp 10 out toward the mouth of the reflector 21. If this direction of movement increases the amount of light received by the photocell 28, the movement continues, but if the light is decreasing, the reversing relay 57 is actuated and the other field winding of the motor 37 is connected to the line conductor 44 causing it to turn in the opposite direction and the lamp 10 to be moved toward the throat or apex of the reflector 21. The increase in light on the photocell 28 causes the vacuum tube amplifier 61 to increase the potential of the direct current applied to the primary 62 of the transformer 63

whereas a decrease in light on the photocell 28 causes the potential applied to said primary 62 to decrease. If the filament 12 is lighted with alternating or modulated current, a rectifier and filter are preferably inserted between the amplifier 61 and the transformer 63 to prevent any fluctuation in the current applied to said transformer 63 other than that produced by movement of said filament 12. With the decrease in potential in the primary 62 of the transformer 63, a positive potential is induced in the secondary 64 which causes the electron tube 65 to pass current and the reversing relay 57 to operate, thereby connecting the second field winding of the motor 37 to the line conductor 44. The transformer secondary 64 is connected to the grid of the electron tube 65 and, through the grid bias battery 66, to the indirectly heated cathode thereof which is also connected to the secondary 68 of the transformer 69. The transformer 69 supplies the plate current to the electron tube 65 to which it is connected at the instant of operation through the coil 58 and the contact engaged by the armature 70 of the reversing relay 57. When the relay coil 58 is energized, the armatures 60 and 70 are shifted causing, first, the line conductor 44 to be connected to the second field winding of the motor 37 and, second, the other relay coil 59 to be connected to the transformer 69 instead of the first coil 58. The primary 71 of the transformer 69 is connected directly to both line conductors 44 and 47 and the other secondary 72 is connected to the heater filament of the electron tube 65.

In whatever direction the filament 12 is moved during which the light falling on the photocell 28 continues to increase, no change takes place until finally the filament 12 passes through the location causing the most light to fall on the photocell 28 and the light begins to decrease. The gradual increase in the amount of light received by the photocell 28 causes the primary 62 of the transformer 63 to continue to increase in positive potential and the secondaries 64 and 73 to increase in negative potential until finally the light begins to decrease, whereupon the secondaries change from a relatively high negative to a positive potential. This potential change is much greater than the similar change taking place with the incorrect movement at the start of operations and causes the circuit controlled by the electron tube 65 to be operated and the relay 57 reversed as well as causing the circuit connected to the transformer secondary 73 and controlled by the electron tube 74 to be operated. The ends of the secondary 73 are connected to the resistance 75, the grid of the tube 74 and through the condenser 76 and the grid bias battery 77 to the indirectly heated cathode of said tube 74. The condenser 76 and resistance 75 prevent the electron tube 74 from passing current when the first light change takes place and have values depending on the other apparatus used. The cathode of the electron tube 74 is also connected to the secondary 78 of the transformer 69 which is connected through the coil 79 of the control relay 80 to the plate of electron tube 74 and which provides the plate current therefor. The passage of current through the coil 79 of the relay 80 pulls the armature thereof, which is connected to the line conductor 44, into engagement momentarily with the lead connected to the armature 81 of the relay 51. The armature 81 is in engagement with a contact connected to the armature 82 of relay 43 which in

turn is in engagement with a contact connected by lead 83 to the coil 84 of relay 51. The coil 84 is energized by the actuation of relay 51 since the circuit therethrough is completed by the lead 5 to the line conductor 47. Energization of the relay coil 84 moves the armatures of the relay 51, causing armature 50 to be moved away from engagement with its associated contact and the circuit to the coil 42 of relay 43 to be broken.

With the coil 42 of the relay 43 not energized, the armatures 53 and 54 are out of engagement with their associated contacts and the circuits to the field windings of motor 37 are broken, causing no further adjustment; the armature 48 is shifted so that it engages a contact connected through lead 86 to the armature 87 of relay 88 and connects the line conductor 44 thereto; and armature 82 is shifted so that it breaks the described connection to the coil 84 of relay 51 and engages the contact connected through leads 45 and 89 to the coil 42 of relay 43. Once the armatures of relay 51 are shifted by the energization of the coil 84, a second circuit thereto is completed through the armature 90 of relay 88 which engages a contact connected through lead 91 to a contact engaged by the armature 92 of relay 51. The armature 92 is connected to the line conductor 44 through leads 93 and 45' and causes the relay coil 84 to continue to be energized even though the circuit through relay 43 is broken at the same time. The function of the relay 51 is to connect the leads from the separate field windings of the motor 35 which are connected to the armatures 94 and 95 thereof to the leads 55 and 56 leading to the reversing relay 57 and the contacts engaged by said armatures 94 and 95.

The motor 35 is operated as in the previous instance in a direction which causes an increase in the amount of light falling on the photocell 28 40 and is stopped by the momentary actuation of control relay 80 when the maximum amount of light falls on said photocell 28. Actuation of relay 80 in this instance causes the line conductor 44, which is connected to the armature thereof, 45 to be connected to the relay contact which is at this time connected through the armature 81 of relay 51, a contact engaged thereby, and lead 96, to the coil 97 of the relay 88. These connections energize the coil 97 which is connected by the leads 98 and 46 to the line conductor 47 and cause the armatures for the relay 88 to be shifted. A second circuit to the relay coil 97 is then completed so as to hold the armatures in this position during this third adjustment by the engagement 55 of armature 87 with the contact connected to the coil 97. As previously described, the armature 87 is connected through the lead 86 and armature 48 of relay 43 to the line conductor 44. The said shifting of the armatures of relay 88 also causes 60 the armature 90 to move away from the contact attached to conductor 91, thereby breaking the circuit from said armature 90 to the coil 84 of relay 51 which permits the armatures of said relay 51 to return to their former position. Armature 81 is moved from engagement with the contact connected to lead 96 and the first circuit to the relay coil 97 is broken. The armatures 99 and 100 are moved into engagement with contacts connected to the field windings of the motor 31 65 and serve to connect the said windings, through the leads 101 and 102 respectively, to the reversing relay 57.

As in the previous instances, the photocell 28 and mechanism connected thereto control the operation of the motor 31 so that the lamp 10 is

finally brought to a position in which the filament 12 is in the correct location or relatively near thereto. In some instances, this operation should complete the operation of our apparatus, but it is preferred to have the apparatus continue through the adjustments a second or even a third time to correct any misalignment. In either case, the operations are automatically repeated by the actuation of relay 80 when the motor 31 finally brings the lamp 10 into position. The relay 80 is 10 operated only momentarily and causes the coil 42 of relay 43 to be energized. The connection is made through the relay 80 to the armature 81 of relay 51 which in turn engages the contact connected to armature 82 of relay 43. The armature 15 82 engages the contact of the lead 89 which is connected to the coil 42 through lead 45. The energization of the coil 42 causes the armatures of the relay 43 to be shifted thereby causing the circuit to the coil 97 of relay 88 to be broken and 20 the other operations already described to follow. The circuit to the coil 97 of relay 88 is broken by the movement of armature 48 of relay 43 away from the contact attached to conductor 86. The adjustments following occur in very rapid order 25 and the collar 14 is then fastened, preferably by solder, to the base 13 before the lamp parts are removed from the machine. A switch may be incorporated in my apparatus to cause operation thereof to be discontinued after a given length of 30 time or a number of cycles of operation, if desired.

What I claim as new and desire to secure by Letters Patent of the United States is:

1. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the said filament to a source of current to cause it to emit light, means located adjacent to said holder for directing light emitted by said filament in a beam in a given direction, light-sensitive means located in the path of the said light beam when the filament is correctly located for receiving the whole of said light beam, and means controlled by said light-sensitive means for moving the said bulb with respect to said holder to cause the said light beam to concentrate on the said light-sensitive means whereby the said filament is located correctly with respect to the said base portion.

2. Apparatus for accurately locating the filament of an incandescent lamp sealed within a bulb with respect to a portion of a base which comprises a holder for the said base portion, means located adjacent the holder for supporting the said bulb with the filament at approximately 55 the desired location, means for connecting the filament to a source of current to cause it to emit light, a parabolic reflector located adjacent to said holder for directing light emitted by said filament in a beam in a given direction, light-sensitive means located in the path of the said light beam when the filament is correctly located for receiving the whole of said light beam, and means controlled by said light-sensitive means for moving the said bulb with respect to said holder to cause the light beam to concentrate on the said light-sensitive means whereby the filament is located correctly with respect to the said base portion.

3. Apparatus for accurately locating the fila-

75

ment of an incandescent lamp sealed within a bulb with respect to a portion of a base which comprises a holder for the said base portion, means located adjacent to said holder for supporting the said bulb with the filament at approximately the desired location, means for connecting the filament to a source of current to cause it to emit light, means located adjacent to said holder for directing light emitted by the filament in a beam in a given direction, a lens located in the path of said light beam for concentrating said light beam, light-sensitive means located behind said lens in the path of the light beam when the filament is correctly located for receiving the whole of said light beam, and means controlled by said light-sensitive means for moving the said bulb with respect to said holder to cause the light beam to concentrate on the said light-sensitive means whereby the filament is located correctly with respect to the said base portion.

4. Apparatus for accurately locating the filament of an incandescent lamp sealed within a bulb with respect to a portion of a base which comprises a holder for the said base portion, means located adjacent to said holder for supporting the bulb with the filament at approximately the desired location, means for connecting the filament to a source of current to cause it to emit light, means located adjacent to said holder for directing light emitted by the filament in a beam in a given direction, light-sensitive means located in the path of the said light beam when the filament is correctly located for receiving the whole of said light beam, a screen disposed between the said light-sensitive means and the holder having an aperture therein through which the light beam passes when the filament is correctly located, and means controlled by said light-sensitive means for moving the said bulb with respect to said holder to cause the light beam to concentrate on the said light-sensitive means whereby the filament is located correctly with respect to the said base portion.

45 5. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the filament to a source of current to cause it to emit light, means located adjacent to said holder for directing light emitted by the filament in a beam in a given direction, a photocell located in the path of the said light beam when the filament is correctly located for receiving the whole of said light beam, means for moving the said bulb with respect to said holder to cause the light beam to concentrate on said photocell, and control means connected to said last-named means and to said photocell for causing the movement of said bulb to take place in such directions as to cause the amount of light falling on the photocell to increase and for causing the movement to be discontinued when the whole of the beam falls on said photocell.

60 6. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the filament to a source of current to

cause it to emit light, means located adjacent to said holder for directing light emitted by the filament in a beam in a given direction, a photocell located in the path of the said light beam when the filament is correctly located for receiving the whole of said light beam, means for moving the said bulb axially back and forth in the direction of said light beam and in two directions at right angles to each other and transverse to said light beam, means connected to said last-named means and to said photocell for causing the movement to take place in each of said directions so as to cause an increase in the amount of light falling on said photocell, and control means for discontinuing the movements in each direction when the amount of light falling on the photocell begins to decrease whereby the filament is correctly located.

7. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the filament to a source of current to cause it to emit light, means located adjacent to said holder for directing light emitted by the filament in a beam in a given direction, a photocell located in the path of the said light beam when the filament is correctly located for receiving the whole of said light beam, means for moving the said bulb axially back and forth in the direction of said light beam and in two directions at right angles to each other and transverse to the light beam, a plurality of electric motors each connected to said moving means for causing adjustment thereof in one of said directions, means including a plurality of electrical relays for connecting each of said electric motors in turn to a source of current, a reversing relay connected to the electric motors and to the photocell for changing the electrical connections to and reversing the direction of motion of said electric motors when the amount of light falling on the photocell decreases, and control means connected to said photocell and to said electrical relays for causing said relays to be actuated to the electric motors to operate and the movement of the said bulb to take place and to cause discontinuation of each of said movements when further movement in each direction causes the amount of light falling on the photocell to decrease whereby the filament is correctly located.

8. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the filament to a source of current to cause it to emit light, means located adjacent to said holder for directing light emitted by the filament in a beam in a given direction, a photocell located in the path of the said light beam when the filament is correctly located for receiving the whole of said light beam, means for moving the said bulb axially back and forth in the direction of said light beam and in two directions at right angles to each other and transverse to the light beam, a plurality of electric motors each connected to said moving means for causing adjustment thereof in one of said directions, means including a plurality of electrical

- relays for connecting each of said electric motors in turn to a source of current, a reversing relay connected to said electric motors and to said photocell for changing the electrical connections 5 to and reversing the direction of motion of said electric motors when the amount of light falling on the photocell decreases, a relay connected to one of said electrical relays and therethrough to each of the other electrical relays for causing 10 operation thereof in turn, means connected to said last-named relay and to the photocell for causing said relay to be operated when the movement of the said bulb either back or forth causes the amount of light received by the said photocell to decrease and a considerable change in 15 potential to occur in said photocell as the filament reaches the correct location or as near thereto as the particular direction of movement permits.
- 20 9. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the filament to a source of current to cause it to emit light, a parabolic reflector located adjacent to said holder for directing light emitted 25 by the filament in a beam in a given direction, a photocell located in the path of the said light beam when the filament is correctly located for receiving the whole of said light beam, means for moving the said bulb with respect to said holder to cause the light beam to concentrate on the photocell, and control means connected to said last-named means and to the photocell for causing the movement of the said bulb to take place in directions which cause the amount 30 of light falling on the photocell to increase and for causing the movement to be discontinued when the whole of the beam falls on said photocell.
10. Apparatus for accurately locating the filament of an incandescent lamp sealed within a bulb with respect to a portion of a base which comprises a holder for the said base portion, means located adjacent to said holder for supporting the said bulb with the filament at approximately the desired location, means for connecting the filament to a source of current to cause it to emit light, a parabolic reflector located adjacent to said holder for directing light emitted 35 by the filament in a beam in a given direction, a photocell located in the path of the said light beam when the filament is correctly located for receiving the whole of said light beam, means for moving the said bulb axially back and forth in the direction of said light beam and in two directions at right angles to each other and transverse to the light beam, a plurality of electric motors each connected to said moving means for causing adjustment thereof in one of said directions, means including a plurality of electrical relays for connecting each of said electric motors in turn to a source of current, an electron discharge tube, a reversing relay connected to said electric motors and to said photocell through said discharge tube for changing the electrical connections to and reversing the direction of motion of said electric motors when the amount of light falling on the photocell decreases, a control relay connected to one of said electrical relays and therethrough to each of the other electrical relays for causing operation thereof in turn, means including a second electron discharge tube connected to said control relay and to the photocell for causing said relay to be operated when the movement of the said bulb either back or forth causes the amount of light received by the said photocell to decrease and a considerable change in potential to occur in said photocell as the filament reaches the correct location or as near thereto as the particular direction of movement permits.

DURYEA E. ELMENDORF.
